UNITED STATES PATENT OFFICE.

ADOLPH VOLLMAR, OF BOSTON, MASSACHUSETTS.

ADJUSTABLE FRONT FOR PIANOS.

SPECIFICATION forming part of Letters Patent No. 690,125, dated December 31, 1901.

Application filed September 13, 1895. Serial No. 562,412. (No model.)

To all whom it may concern:

Be it known that I, ADOLPH VOLLMAR, of Boston, county of Suffolk, State of Massachusetts, have invented an Improvement in Adjustable Fronts for Pianos and the Like, of which the following description, in connection with the accompanying drawings, is a specification, like letters on the drawings representing like parts.

10 My invention relates to devices for automatically moving the swinging front or rack of a piano or equivalent article or instrument from and by the fall or cover for the keys or operating devices, the object of my invention being to simplify and improve the construction 15 of devices of this nature.

Figure 1 is a sectional view of the upper front portion of a piano-frame with my device attached, and Fig. 2 is a similar view with 20 the swinging front thrown forward into position to receive a sheet of music or a book.

In the drawings and specification, A indicates the piano-frame, whose "rails" a a', "swinging front" B, "key-block" C, "cloth strip" D, "shelf" E, and "fall" F may be and 25 preferably are of usual construction.

In the embodiment of my invention selected for illustration, H is a vertical rod or tube of suitable dimensions and material, loosely 30 mounted in bearings in the horizontal front rails a a' of the frame A and adapted to actuate the swinging front B. The motion of the actuating-rod may be communicated to the swinging front or rack in various ways, 35 the means illustrated comprising a cam b and its coöperating projection h, mounted in this instance upon the swinging front and rod, respectively, though this order of arrangement is not obligatory. The cam b is preferably 40 slotted at b' to provide for the positive operation of the front or rack both forward and backward, this being effected by the play in the slot of a projection h on the actuating-rod, which projection, as herein illustrated, 45 consists of a pin h, set in a collar h', made adjustable on the rod by a set-screw h². Downward movement of the rod in the present arrangement of the cam and its coöperating pin serves to bring the pin into operative en- 50 gagement with the cam-surface b³, and thereby to force the front board or music-rack outward into the position shown in Fig. 2. Up-

ward movement of the rod carries the pin h against the opposite surface b³ of the cam, and in the arrangement shown the front is 55 positively returned to its normal closed position and there held, as indicated in Fig. 1. The downward motion of the actuating-rod, and consequently the advance of the front, in the present instance, is derived from the 60 opening movement of the fall F, the construction and mode of operation of which varies in different "makes," but which is herein illustrated as of the common double form, jointed at f and hinged to the cloth strip D at f'. 65

As one means of operatively connecting the fall and actuating-rod I have affixed to the rear part of the fall and within the case an arm or lever f³, shown as provided with a roller r and adapted to engage the outwardly-extended end h⁴ of a bracket h³ on and near the lower end of the actuating-rod and beneath the bearing-rail a'. This bracket is made adjustable upon the rod H by means of the set-screw h⁵ and is preferably bent or 70 curved, as indicated, to clear the keys, &c., when, as often happens, it becomes necessary to remove the entire part of the piano-front above the keyboard. The arm f³ may be provided with a spring-catch, as f⁵, to insure 75 when the piano is in use the retention of the lever-arm at its lowest position, at which time the spring will enter a recess c or contact with the inner side of the key-block C, which is cut away at c' to allow for the necessary range of movement of the arm f³ and bracket end h⁴. (See dotted lines, Fig. 2.) When the fall is drawn over to cover the keyboard, the bracket h³ of the actuating-rod is released, and the return of the operating 80 parts to normal position is effected by the tendency of the swinging front B to fall inward of its own weight. To insure complete closure, however, I have provided an auxiliary spring S, shown as coiled about the rod 85 H and fastened to the adjustable collar h' thereon, the spring being affixed at its upper end to the bearing-rail a and normally tending to hold the rod in its uppermost position, as shown in Fig. 1. 90

Any suitable means for connecting the fall and actuating-rod may be used, and my invention is not limited to any specific form; but I prefer to leave the arm f³ and bracket 95 100

end h^4 entirely independent, as illustrated, in order to guard against possible injury to the mechanism by carelessness or inefficiency on the part of the piano-tuners, for by this arrangement after removal of the shelf E, as usual, the removable front portion of the piano-frame may be tilted forward and lifted out in the ordinary manner, carrying with it the standard a^4 , the swinging front B, the rails $a' a'$, and the actuating-rod H, with its bracket h^3 , spring S, &c., mounted on said rails, leaving only the independent fall and arm f^3 in the case. In the same manner the front, carrying with it the device, may be replaced, as usual, and without requiring any special skill or knowledge by the operator of the mechanism.

To augment the rigidity of the rod H, the bracket h^3 may have a flat extension at its inner end, as at h^6 , and a block, as a^5 , fastened to the frame, may be provided to furnish a bearing-surface. This, however, may be omitted, if desired, as may also the stop T, (best shown in Fig. 2,) the function of whose recess t is to receive an extension of the pin h to prevent the spring S from twisting the operating parts to an undesirable extent when the piano-front is removed.

To avoid rattling, the parts are covered with felt at the contacting points, as 1 2 3 4 5 6.

Obviously my device may be utilized to throw forward the entire swinging front of any suitably-constructed instrument or equivalent device or any desired part thereof—as the music-rack, for instance—and my invention comprehends all such uses.

I am aware that it is not broadly new to provide means for advancing the music-rack of a piano automatically when the fall is raised, nor do I make such a claim; but

What I do claim, and desire to be protected upon, is—

1. In a device of the class described, a frame, its swinging front and movable fall, a vertically-movable actuating-rod operatively connected with said swinging front, a bracket upon said rod near its lower end, and

an actuating-lever therefor on the fall for moving the actuating-rod to operate the swinging front, substantially as described. 50

2. The combination with an upright frame, its swinging front and movable fall, of an actuating-rod vertically reciprocable in suitable bearings upon the frame and provided with a horizontal actuating-lug, a cam upon 55 the swinging front adapted to be operatively engaged by the said lug, a bracket upon said rod near its lower end and an actuating-lever therefor on the fall for moving the actuating-rod to operate the swinging front, substantially as described.

3. In an apparatus of the class described, an actuating-rod and its bracket, a fall-arm to operate said bracket, and an antifriction-roller intermediate said bracket and fall-arm 65 to diminish the friction therebetween and prevent accidental displacement of one relative to the other, substantially as described.

4. In an apparatus of the class described, an actuating-rod, a bracket thereon having 70 its upper surface knife-edged, a forked fall-arm to operate said bracket, and a friction-roller mounted in the fork of said fall-arm and grooved to receive said edged surface to prevent accidental displacement of the said 75 arm and bracket relative to each other, substantially as described.

5. In a device of the class described, a frame, its swinging front and movable fall, a vertically-movable actuating-rod operatively connected with said swinging front, a bracket or offset upon said rod near its lower end, and a transmitting member intermediate the bracket and fall and adapted to be actuated by the latter to operate the former 85 to move the swinging front, substantially as described.

In testimony whereof I have signed my name to this specification in the presence of two subscribing witnesses.

ADOLPH VOLLMAR.
